UNITED STATES PATENT OFFICE.

CYRUS HOWARD HAPGOOD, OF NUTLEY, NEW JERSEY, ASSIGNOR TO THE DE LAVAL SEPARATOR COMPANY, OF NEW YORK, N. Y., A CORPORATION OF NEW JERSEY.

MEANS FOR CONTROLLING THE FEED OF GASOLINE ENGINES.

Application filed March 30, 1926. Serial No. 98,423.

In the operation of gasoline farm engines it is the practice, especially in cold weather, to open up the gasoline valve in starting so that a very rich mixture of gasoline and air is fed 5 into the cylinder. As it is necessary, after starting, to continue to supply a fairly rich mixture until the engine warms up to its running temperature, the gasoline valve, especially in cold weather, is left open to a point 10 where too much gasoline is being fed to the engine when running temperatures are reached. This excess of gasoline results in not only a waste of gasoline itself, but in the fouling of the cylinder and spark plug with 15 carbon due to incomplete combustion, with resultant impairment of lubrication and operation.

The object of the invention is to automatically control the feed of gasoline to 20 the engine so that, in starting, gasoline will be fed to the engine at a maximum rate, giving a rich mixture, and so that, as the engine warms up, the rate of gasoline feed will be reduced until, when the engine 25 reaches its running temperature, the feed of gasoline will be reduced to the rate desired for such running temperature.

The object is accomplished by the means shown in the accompanying drawings, 30 which represent a preferred embodiment of my invention, and wherein—

Fig. 1 is a side view, partly in section, of the engine cylinder, the water jacket and hopper, the feeding means, and the feed 35 regulating means.

Fig. 2 is a detail view of the feeding means.

The cylinder *a* contains a piston *b* and is surrounded by a water jacket *c* fed from 40 a water hopper *d*. The cylinder is provided with the usual spring-actuated intake valve *f* and discharge valve *e*.

A known type of mixing or generating valve structure is shown in Fig. 2. The casing *m* encloses a mixing chamber and has an outlet for the gasoline and air mixture 45 communicating with the passage *g* to the intake valve *f*. The casing has an air inlet at its lower end controlled by a valve *h*. Threaded in the cover of the valve is a choke 50 rod *i* extending through the interior of the casing and limiting the lift of valve *h*. Valve *h*, when seated by the action of its actuating spring *j*, closes the air inlet and also closes 55 a port communicating with a gasoline intake

passage *k*. The passage *k* is formed in an extension from the casing, in which extension is also formed an orifice that receives a needle valve *n*. Valve *n* also extends through packing *p* and a packing nut *o*. The stem 60 of valve *n* projects beyond nut *o* and is threaded on the end to receive a nut *r*, between which and nut *o* is confined a spring *s*.

In my invention the adjustment of the needle valve is such that it will open, when 65 the spring is allowed to expand to its maximum extent, to allow a maximum feed of gasoline, so as to give a supply sufficient to start the engine when cold.

A bushing *t* is screwed into one side of the 70 water hopper. Secured to this bushing and extending through the interior of the water hopper is a brass tube *v* having a closed end *u*. Secured to the closed end of the brass tube *v* is a nickel steel rod *w*, which extends 75 through and beyond the open end of the tube *v*. The projecting part of the rod *w* extends through the upper end of a lever *y*. The extremity of the rod, beyond lever *y*, is threaded and receives an adjusting nut *x*. 80 Lever *y* is pivotally supported between its ends on an ear *z* on the head of the cylinder. The lower end of the lever *y* extends opposite the end of the needle valve *n* and limits its outward movement. A longitudinal 85 movement, in the direction of the arrow, of rod *v* is, through adjusting nut *x*, transmitted to lever *y*, which in turn moves needle valve *n* inward, that is, in the direction required to throttle the gasoline passage. 90

The coefficient of expansion of brass is .0000105. The coefficient of expansion of 36% nickel steel is .0000004. The difference in expansion is therefore .0000101.

If it be assumed that ten inches of the 95 brass tube *v* is exposed in the body of water and that the variation in temperature of the water is from 42° F. in cold weather to a running temperature of 212° F. (or 170° F. variation), the differential motion of rod *w* 100 will be .017 inch.

If it be assumed that the ratio of the two arms of the lever *y* be 1:2, then the motion of the needle valve *n*, due to the described thermostatic couple, will be .034 inch, which 105 is ample for all needs.

The adjustment is such that when the tube and rod are cool and contracted, the lower end of lever *y* is positioned to allow the needle valve to open to the full extent re- 110

quired for starting thereby giving a mixture rich in gasoline. As the temperature of the water rises, both the brass tube *v* and the nickel steel rod *w* expand in length, but the expansion of rod *w* being relatively slight, its free end will move in the direction of the arrow, and nut *x*, engaging lever *y*, will swing the lever so as to push in the needle valve and gradually throttle the gasoline admission passage, until, when the water is raised in temperature to the boiling point, the needle valve throttles the gasoline passage to the degree adapted to yield the desired lean gasoline mixture suitable for running conditions.

15 After the engine is shut down and the water cools, the brass tube in the water hopper contracts to a greater degree than the nickel steel rod, thereby causing a movement of adjusting nut *x* opposite to that indicated by the arrow. Nut *x* therefore recedes from lever *y*, and spring *s*, not being restrained by lever *y*, opens the needle valve to the degree required to supply sufficient gasoline when the engine is re-started. After the engine is 20 re-started and the water hopper warms up, the reverse action takes place, as above described, and the needle valve is gradually closed until the water in the hopper reaches the boiling point.

25 The gasoline-control valve therefore requires no manual adjustment.

30 While I have described the tube as composed of brass and the rod as composed of nickel steel, any two materials having substantially different coefficients of expansion will be operative. For example, steel and hard rubber make a good combination. Aluminum and glass, or hard rubber and wood, are examples of other practicable combinations. It is obvious, also, that the rod 35 may have a higher coefficient of expansion than the tube and that such a construction would be operative if accompanied by obvious changes in the connections to the needle valve. It is also obvious that the two materials need not take the form of a tube and a rod respectively, and that other embodiments of the invention than that shown would be 40 within the scope of the claims. I do not, however, herein claim my invention in its broadest embodiment, as such claims are set forth in an application filed of even date herewith, Serial No. 98,424.

45 Having now fully described my invention, 50 what I claim and desire to protect by Letters Patent is:

55 1. In an internal combustion engine, the combination with an engine cylinder, a chamber adapted to contain water and maintain a water jacket around the cylinder, means pro-

viding a passage for admission of gasoline to the engine, and a movable valve governing the rate of gasoline inflow, of a tube extending in the direction of extension of the cylinder and throughout the major part of the length of said chamber, said tube being open at one end and closed at the other, the open end of the tube extending into an orifice in the chamber wall and being supported by said wall, its closed end being unsupported, a rod 65 having a coefficient of expansion different from that of the tube and one end of which is secured to the closed end of the tube and which extends throughout the length of the tube and beyond its open end, temperature 70 changes in the water therefore effecting a longitudinal movement of one end of the rod with the closed end of the tube while the other end of the rod has a longitudinal movement relative to the open end of the tube, and 75 means, actuatable by the rod in its longitudinal movement, adapted to control the position of the valve to effect a closing movement of the valve as the water warms and an opening movement of the valve as the water cools. 80

2. In an internal combustion engine, the combination with an engine cylinder, a chamber adapted to contain water and maintain a water jacket around the cylinder, means providing a passage for admission of gasoline to 90 the engine, and a movable valve governing the rate of gasoline inflow, of a tube extending in the direction of extension of the cylinder and throughout the major part of the length of said chamber, said tube being open 95 at one end and closed at the other, the open end of the tube extending into an orifice in the chamber wall and being supported by said wall, its closed end being unsupported, a rod having a coefficient of expansion substantially less than that of the tube and one end of which is secured to the closed end of the tube and which extends throughout the length of the tube and beyond its open end, temperature 100 changes in the water therefore effecting 105 a longitudinal expansion and contraction of the tube, thereby bodily pulling the rod inwardly in the tube in the latter's expansion and bodily pushing the rod outwardly in the tube in the latter's contraction, and means, 110 actuatable by the rod in its said bodily movements, adapted to control the position of the valve to effect a closing movement of the valve as the water warms and an opening movement of the valve as the water cools. 115

In testimony of which invention I have hereunto set my hand, at New York, on this 18th day of February, 1926.

CYRUS HOWARD HAPGOOD.
